ATTORNEYS

UNITED STATES PATENT OFFICE.

HARRY N. ANDREASEN, OF CHICAGO, ILLINOIS.

DIME-SAVINGS BANK.

Application filed March 19, 1923. Serial No. 626,094.

To all whom it may concern:

Be it known that I, HARRY N. ANDREASEN, a citizen of the United States, and a resident of Chicago, in the county of Cook and

5 State of Illinois, have invented a new and useful Improvement in Dime-Savings Banks, of which the following is a full, clear, and exact description.

10 My invention relates to improvements in savings banks for small coins, such as dimes and the like, and it consists in the combinations, constructions, and arrangements herein described and claimed.

15 An object of my invention is to provide a dime savings bank which may be carried in a pocket of the owner in a manner similar to that of a fountain pen, so that dimes which may be received in change may be immediately deposited, thereby insuring 20 their retention in instances where, if left in the pocket to be deposited later, they may be spent.

25 A further object of my invention is to provide a dime savings bank, which is relatively narrow, so as not to bulge out the pocket, this being accomplished by means of an inclined bottom which will stack the dimes in inclined position, thereby permitting the receptacle to be made narrow.

30 A further object of my invention is to provide a cap, having a slot with curved walls adjacent thereto, so that the dime is quickly guided to the slot no matter at what angle it is presented.

35 A further object is to provide a cover having a slot which will prevent the shaking of the dimes from the receptacle, and thus making it difficult for one, or even impossible, to extract a dime, without re- 40 moving the head or cap.

45 A further object is to provide a head or cap portion which is held by a spring latch, but which may be easily removed by inserting a key or tool of a special type, this key being designed to be kept by the banking institution.

50 A further object is to provide a head or cap which may be instantly replaced and locked in position, and which is provided with a spring clip for holding the bank securely to the pocket or clothing of the owner.

55 Other objects and advantages will appear in the following specification, and the novel features of the invention will be particularly pointed out in the appended claims.

My invention is illustrated in the accompanying drawings, forming part of this application, in which—

Figure 1 is a front elevation,

60 Figure 2 is an enlarged section along the line 2—2 of Figure 1,

Figure 3 is a top plan view, and

Figure 4 is a view of a key used in unlocking the device.

65 In carrying out my invention, I provide an elongated receptacle, preferably of metal, but which may be of any suitable material, and which has an elliptical cross section. In the drawings, I have shown a body portion 1. It will be observed that the bottom 2 is made on an incline, so that the dimes 3 will be stacked in inclined position. This permits the receptacle to be made relatively narrow, and yet of dimensions at right angles to its narrowest width, which will easily accommodate the coins. The upper part of the elliptical receptacle 1 has stamped inwardly therefrom a lug or keeper 4.

70 The head or cap consists of a cylindrical body portion 5, having downwardly extending guide members 6 arranged to enter and engage the walls of the receptacle 1. An extension 7 is provided with an opening 8, and is curved inwardly at its bottom, as shown at 9. This extension is, in fact, a spring locking member. The upper portion of the cap or head is rounded at 10 in the manner shown in Figures 2 and 3, and 75 is provided with a central slot 11 which extends at right angles to the smallest width of the receptacle. A spring clip 12 is provided, which is integral with the cap, and which, of course, is removed when the cap 80 is removed. It will be observed that the walls of the slot 11 extend toward the interior of the receptacle, when the cap is in position, for a purpose to be explained later.

85 From the foregoing description of the 100 various parts of the device, the operation thereof may be readily understood. As has been stated before, the purpose is to provide a savings bank in which all dimes that come into the possession of the owner may 105 be immediately deposited in a place where the owner himself cannot have access to them. In this way, many dimes will be saved which might otherwise be spent uselessly. The bank is held in the pocket by 110 means of the spring clip 12 in the manner similar to the holding of a fountain pen or

a pencil. The coins are very readily deposited, since the curved portions 10 really form an enlargement of the slot 11, so that when the dimes are presented from almost any angle, they will readily be guided into the slot. As the dimes fall into the receptacle, they take an inclined position, and it is the fact that the dimes are inclined that enables the receptacle to be made narrower, and yet to provide ample room for the coins.

In the present device, I have not shown any means for indicating the number of dimes in the bank, although it might be shown, without departing from the spirit 15 of the invention.

When the owner desires to deposit the money in his banking institution, he goes to the bank, where a key 13, like that shown in Figure 4, is kept. This is inserted 20 through the slot 11, is passed underneath the end 9 of the spring member 7, and then is pulled so as to cause the spring to be disengaged from the lug 4, when the cap may be instantly removed.

In order to replace the cap, all that is necessary is to insert it in the end of the receptacle and force it downwardly, when the spring will guide over the lug 4, until the opening 8 is reached, when it will spring 30 underneath the lug, thus retaining the cap in locked position.

I desire to call particular attention to the fact that it is very difficult, if not impossible, for any one to remove a dime by shaking 35 the receptacle. If, when the receptacle is inverted, it is shaken, the edges of the coins will ordinarily be deflected past the slot and into the curved portions on either side thereof, and the only way of shaking 40 out a dime would be to shake it so that the dime would be exactly in alinement with the slot and exactly in the plane of the longitudinal axis at a time when it is approaching the slot. This would not happen in 45 many thousand times, so that it can be readily seen that it is a useless attempt to extract a dime, without removing the cover.

While I have spoken of metal as being the material of which the device can be made, 50 obviously it could be made of any material, and indicating means, such as a slot in the side of the device, might be made, without departing from the spirit and the scope of the invention. The device would also work 55 for coins other than dimes, although the primary object of the invention is to provide a dime savings bank, as stated.

I claim:

1. A coin bank, comprising an elongated 60 receptacle of elliptical cross-section, with the bottom arranged at an inclination adapted to permit the coins to lay parallel therewith, a removable cap provided with a coin-receiving slot and with a flange 65 adapted to enter the receptacle, a portion of

the flange being adapted to flex and provided with a socket, and a lug on the receptacle interior adapted to enter said socket and thereby lock the cap in place.

2. A coin bank, comprising an elongated 70 receptacle provided with a sloping bottom adapted to permit the coins to lay parallel therewith, the bottom and side walls being arranged to provide a wedge shaped end to the receptacle, the interior of the receptacle 75 being provided with a lug, a coin receiving slot in the upper end of the receptacle, one of the end walls being removable and provided with a flange adapted to extend into the receptacle and provided with a flexible 80 portion having a socket adapted to receive said lug, and means insertible through said slot, adapted to engage with the flexible portion, whereby said portion may be released from said lug. 85

3. A coin bank, comprising an elongated receptacle having a sloping bottom adapted to receive the coins in an inclined parallel relation, a removable cap having a flexible 90 portion adapted to enter the receptacle and form locking relation therewith and a coin introducing slot, said cap being provided with a resilient extension disposed lengthwise of the receptacle exterior adapted to constitute a fastening clip, and means arranged to pass through the coin-slot and adapted to engage with said flexible portion to flex the latter out of locking position. 95

4. A coin bank, comprising an elongated 100 receptacle of elliptical cross-section, with the distance between the front and rear walls less than the diameter of the coin for which the bank is intended, the walls being of different lengths and one wall on its interior being provided with a keeper or lug, a bottom sloping wall connecting the two side walls and formed to permit the coin to lay flush with the bottom and in contact with the two side walls, and a removable cap provided with a flange adapted to enter the end of the receptacle, a portion of the flange being extended downwardly within the receptacle and adapted to flex, said portion being formed to engage with the keeper or lug to lock the cap in place, the cap being provided with a coin-receiving slot. 110

5. A coin bank, comprising an elongated 115 receptacle elliptical in cross-section and of less dimensions from front to rear than the diameter of the coin for which the bank is intended, the receptacle bottom being inclined and adapted to have the coin lay flush therewith, and a single piece cap, provided with a coin receiving slot, formed to provide a flange adapted to enter one end of the receptacle and having an extension adapted to extend lengthwise of the receptacle to provide a clothing engaging clip. 120
